HYDROSTATIC FUZE

José Mena y Vieyra de Abreu, Madrid, Spain

Application October 24, 1955, Serial No. 542,450

Claims priority, application Spain November 10, 1954

7 Claims. (Cl. 102—7)

The present invention relates to a new fuze applicable to underwater projectiles and particularly to depth charges for use against submarines.

This fuze will ensure an underwater explosion of the projectile or the depth charge, with such precision as to the calculated depth, that its absolute and relative errors are technically insignificant.

The mechanisms thereof operate in combination with a normal hydrostatic pressure. Provision is made to prevent detonation due to an abrupt excess of pressure, so that the explosion of other mines exercise no effect on their correct performance.

Furthermore, provision has been made to block all mechanisms in order to prevent their performance until the charge has reached a predetermined depth of, for example 10 meters, thereby avoiding all risks to any craft launching such devices.

The novel fuze is likewise provided with all safety devices required of this kind of projectile, both for their storage as also for the transport and manipulation thereof.

These safety devices by no means interfere with the perfect performance of the apparatus and are achieved by a very reduced number of proficiently arranged elements, whereby within a few seconds, the entire mechanism can be removed from the depth charge for an inspection thereof.

The desired depth can be set instantaneously, or changed at will, either to increase or reduce the depth of explosion. Said regulation of depth can be performed within a few seconds and set as often as required.

It will be understood that with this device, technically, there is no need to limit the maximum depth of explosion, as all elements can operate at any depth. In practice, its use is generally confined to the maximum depth apt to be reached by a submarine.

Moreover, absolute watertightness has been provided for, thereby preventing deterioration of the mechanism and explosive charge.

For a better comprehension of the invention, the accompanying drawings represent, in:

Fig. 1, a longitudinal section of the fuze;

Fig. 2 shows a perspective view of the depth setting and indicator device;

Fig. 3 shows the spring compressor element;

Fig. 4 shows a perspective view of the fluted sleeve;

Fig. 5 shows a development of the lower portion of the compressor element shown in Fig. 3;

Fig. 6 shows a partial view of the sleeve which externally sheathes that portion of the fuse showing the depth marked by the indicator;

Fig. 7 shows a plan view of the graduated index disc;

Fig. 8 shows a sectional view of the safety device between the primer and the booster; and

Fig. 9 shows a sectional view of the device shown in Fig. 8 at the time the fuze operates.

The fuze body 22, Fig. 1, is constituted by a cylindrical element the upper portion of which has an externally threaded central shank 22a to which is screwed a depth regulator. Underneath the depth regulator is a circular

2

flange 22b for the accommodation of a dual setting disc 12 and on which is a threaded ring 22c to which is threaded a cap 1. The fuze body is threaded at 22d to hold the fuze in the projectile casing. The flange 22b is turned by a wrench the teeth of which engage with several holes 22e. Between the flange and the projectile casing may be placed a resilient gasket of rubber or other appropriate material for insuring a watertight joint. Within the fuze body 1 is an axial cylindrical bore 22f within which is slidably mounted a tube 5. The bore 22f is enlarged within the shank 22a to accommodate locking balls 36 which are set in holes in the end of tube 5.

An expansion chamber 42 is provided within fuze body 22 and is closed by a gasket 43 which is held in place by a washer 44.

A cylindrical casing 23 is threaded to the end of fuze body 22, and within the lower end of the cylindrical casing 23 is threaded a fluted tube 45 having flutes 16 on the outside thereof. At the end of the fluted tube 45 within 20 the cylindrical casing 23 is a groove 46.

Attached to the tube 5 is a sleeve 4, which extends within the cylindrical casing 23 and the end of which surrounds the grooved end of fluted tube 45. The sleeve 4 together with the tube 5 forms a spring compressor element. On the inside of the end of sleeve 4 surrounding the fluted tube 45 are two wedges 15 which project into the groove 46.

Sleeve 4 has a plurality of apertures in the wall thereof which are spaced both circumferentially and axially from 30 each other along the entire length of the sleeve. In the embodiment shown, two sets of apertures are provided, one aperture in each set having a diametrically opposed aperture in the other set.

Within the end of the fluted tube 45 is slidably fitted a 35 primer piston 19, in the upper end of which is a pair of diametrically opposed slots 18a. Fluted tube 45 has a pair of diametrically opposed apertures 46a in the end thereof within the sleeve 4, and positioned within these apertures are locking detent balls 18 which project into 40 the grooves 18a on the primer piston 19. On the end of the primer piston 19 is a primer casing 20 within which is a primer 21 and a detonator cap 7.

A spring 6 is provided between the end of the sleeve 4 attached to the tube 5 and the primer piston 19. In 45 the position of the parts shown in Fig. 1, the spring is unstressed.

Threaded into the end of the fluted tube 45 where it is attached to the cylindrical casing 23 is a cap 39 within which is a safety device to be described below. Threaded 50 into the cap 39 is a booster casing 27 containing a booster charge 26 having an axial bore 26a therein. Within the axial bore 26a is a firing pin 8 which is pointed toward the primer 21.

The depth setting device comprises an inner adjusting member 11 which is threaded over the shank 22a and which has the tube 5 projecting therethrough. At the point where the tube 5 passes through the inner adjusting member 11, the outside diameter of the tube 5 is reduced so that when inner adjusting member 11 is screwed onto 60 the shank, tube 5 will be moved into the fuze body 22.

Over the inner adjusting member is a cover member 9 which is rotatably mounted on the inner adjusting member 11, and which has depending therefrom dual pointers 10 which extend downwardly to the fuze setting disc 12. Through the cover member 9 is a diametrical bore 13a, and in the end of the tube 5 are two apertures 14 which may be aligned with the bore 13a. A safety pin 13 may be inserted through the bore 13a and the apertures 14, and held therein by the arm 13b.

In the cap 1 are two valves 29 each consisting of a 70 housing 2, 3 having an aperture 30 on the inner end thereof, and having a spring loaded plug 31 therein which is spring loaded outwardly by spring 32.

Within the upper end of tube 5 is a gland 33. Adjacent the lower end of gland 33 are a plurality of grooves 35 in the tube 5. Gland 33 has a transverse bore therethrough within which are mounted spring loaded balls 34 which are spring loaded outwardly and which normally engage in one of the grooves 35.

In the cap 39 threaded into the lower end of fluted tube 45 is a transverse passage 28a within which are two rollers 28 held in place by spring loaded balls 38 engaging in a groove 40 along the wall of passage 28a. The rollers 28 are normally in contact with each other as shown in Fig. 8.

In the wall of the cylindrical casing 23 adjacent the end of sleeve 4 is an opening 24, and depth setting corresponding to the settings on the fuze setting disc 12 are printed on the end of sleeve 4 on a level with the opening 24.

The number of spaces between the flutes 16 on fluted tube 19 is one greater than the number of pairs of opposed apertures 17. The spacing of the flutings is such that the spaces between them are vertically aligned with the apertures 17 in the sleeve 4.

As the hydrostatic pressure operates upon the compressor element 4, 5, it is caused to descend, compressing the spring 6, which thus accumulates sufficient force to fire the primer 7, which upon striking the firing pin 8, produces the explosion. The depth at which this detonation is to be produced, is set by means of the depth setting device. By the rotation of said pointers 10 to mark the desired depth on the graduated disc, the compressor element 4, 5 is also caused to rotate, as pin 13 engages the tube 5 and the casing 9, thus placing the two internal wedges 15 at the lower end of the compressor element so that they will register with the entrance of two of the flutes on the fluted sleeve 45. This will cause the compressor element to descend in the axial direction by the sliding action of said wedges in the referred to flutes or channels.

The locking detent balls 18 provided in the openings in the upper portion of the fixed fluted sleeve 45 prevent a descent of the primer piston 19 until they escape. The spaces between flutes 16 in the fluted sleeve 45 are arranged in such a manner that the balls 18 will register with that pair of openings 17 that has been aligned therewith by the fuse setting device, which openings are placed at a higher position in the sleeve 4 the greater the depth at which the detonation of the charge is required.

To set the explosion depth, the cap 1 is removed temporarily in order to rotate the cover member 9 on the depth setting device in the desired direction so that the two pointers 10 thereof will coincide on the graduated disc 12, with the desired detonation depth. While maintaining said cover member 9 in this position, the internal element 11 of the depth setting device is screwed down, whereby the compressor element is immobilized, since the two wedges 15, which heretofore rotated freely in the slot 46, see Figs. 1 and 4, will have entered two channels on sleeve 45.

Thereafter, by removing the pin 13 and replacing the cap 1, the fuse is prepared to operate under the influence of hydrostatic pressure.

After having set the depth at which the explosion is to occur, the charge is ready for launching. As the charge enters the water, the hydrostatic pressure is increased, thereby opening the valves 31, so that the water will fill the interior of the cap 1 and penetrate through the bores previously occupied by the pin 13 to the tubular sleeve 5 where it will meet with the resistance of the gland 33 that closes said tube.

As soon as the charge reaches eight or ten meters, but not before, the water pressure will be able to push said gland 33 inwards to overcome the predetermined resistance of the two spring loaded balls 34 against the inner walls of the tubular sleeve 5 in which successive detonation slots 35 are provided. By this safety feature, the

mechanisms are kept blocked, preventing their performance, while the charge reaches a minimum depth of eight or ten meters, or any other predetermined depth, so that under no conditions the charge can explode in the proximity of the launching craft.

While the gland 33 occupies the position shown in the drawing, or with the two balls 34 held in any of the successive slots 35, the tube 5 cannot descend, the balls 36, lodged in the walls of said shank being pushed outwardly by the gland 33 and protruding a sufficient distance into slots 47 to prevent the descent.

After the water has pushed the gland 33 to the bottom of the tube 5 the balls 36 will offer no further resistance, as they will now fall into tube 5.

By the progressive advance of the compressor element, the spring 6 will be compressed until the two bores 17 situated vertically above the two balls 18 register therewith, at which moment the balls 18 escape. Piston 19 is then free and is then impelled downward by the spring 6. At this moment, the primer tube 20, forming a conical wedge, will penetrate between the rollers 28, see Fig. 8, and thus advance until the primer strikes against the point of the firing pin 8, see Fig. 9, thereby causing an explosion in the very center of the booster 26.

The two rollers 28, see Figs. 8 and 9, placed in parallel and in contact with each other, serve as a safety device to break the shock wave, liable to be produced by an untimely explosion of the primer 7. Fig. 8 shows the position of said rollers 28 prior to their separation by the conical point of the primer tube 20, and Fig. 9 shows said rollers after their separation, thus permitting the passage of the primer tube 20 toward the firing pin 8. The rollers 28 are held in contact by a slight pressure of the spring 37, which compresses the balls 38 against the walls of the lower plug 39, which is in turn provided with slight cavities 40 on the internal walls thereof.

The pin 13, which transmits the rotation of the indicator 9 to the tube 5, likewise constitutes a safety device, since while it is fixed in its normal position it will prevent a descent of the compressor element, the upper end of which is traversed by the pin 12 which has to be removed before the device will operate.

The flutes 16 tend to keep the balls 18 aligned with the selected pair of bores 17 for each depth. However, there is a pair of flutes that do not coincide with any pair of bores, so that by placing the indices 10 on the cap 9 of depth setting device 11 in the position marked with the thick line 41, the fuze cannot operate, since the wedges 15 register precisely with the only pair of flutes 16 that do not permit balls 18 to coincide with any of the bores 17.

If a small amount of water should penetrate between the compressor element and the fuze body 22, a cavity 42 has been provided wherein it will be retained by means of a resilient gasket 43, which is compressed by the threaded washer 44.

If, after the charge has been launched, an abrupt excess of pressure should occur, for example, from another mine or depth charge, the plugs 31 in the valves 29 would then descend to the bottom overcoming the resistance of their springs 32, and thus closing the bores 30 and preventing the passage of water pressure into the fuze.

What I claim is:

1. A hydrostatic fuze for use in underwater explosive devices comprising a fuze body engageable in the explosive device and having an axial bore therethrough, a cylindrical casing attached to one end of said fuze body, a spring compressor element having a tube slidably in said bore and a sleeve fixed to the end of said tube within said cylindrical casing, said sleeve having a plurality of apertures in the wall thereof spaced circumferentially and axially of said sleeve from each other, a wedge on the end of said sleeve opposite said tube projecting radially into said sleeve, a fluted tube attached within the end of said cylindrical casing opposite said fuze body and extending within the end of said sleeve, said fluted tube having a

groove around the outside of the end thereof within said sleeve into which said wedges project, each of the flutings being vertically aligned with one of said apertures in said sleeve, a detent locking ball in the end of the wall of said fluted tube within said sleeve, a primer piston slideable within said fluted tube having a groove therein in which said locking detent ball is engaged, a spring between said primer piston and said sleeve normally in the unstressed condition, a primer on the end of said primer piston opposite said spring, a booster having an axial bore therein attached on the end of said cylindrical casing with the bore aligned with said primer, a firing pin in said bore, means between said primer piston and said booster for blocking a shock from the explosion of said primer and for permitting passage of said primer, depth setting means on the end of said tube opposite said sleeve for rotating said tube and said sleeve and for urging said tube and sleeve toward said primer piston, gland means held in the end of said tube adjacent said depth setting means for keeping water pressure from within said tube until a predetermined pressure has been reached, and a cap over said depth setting means having a valve therein for admitting water to said fuze.

2. A hydrostatic fuze as claimed in claim 1 in which said means between said primer piston and said booster comprise a pair of spring loaded rollers in contact with each other, a plug in the end of said fluted tube having openings therein in which said rollers are movable, and the end of said primer being beveled.

3. A hydrostatic fuze as claimed in claim 1 in which said depth setting means comprising an inner adjusting member threaded to said fuze body, a cover member rotatably mounted on said inner adjusting member and having pointer means thereon and a bore therethrough, said tube having apertures therein in alignment with said bore, and a pin through said bore and apertures.

4. A hydrostatic fuze as claimed in claim 1 in which said gland means comprise a gland slidably fitted in the end of said tube and having an opening therethrough, the interior of said tube having a groove therein, and a spring

35

40

loaded locking ball in said opening in said gland and projecting into said groove.

5. A hydrostatic fuze as claimed in claim 1 in which all but one of the flutings on said fluted tube are aligned with one of said apertures in the wall of said sleeve.

6. A hydrostatic fuze as claimed in claim 1 in which said valves in said cap having a spring loaded plug therein are spring loaded outwardly, and have an aperture beneath said plug, whereby a sudden hydrostatic pressure causes the plug to overcome the spring loading and close said aperture.

7. In a hydrostatic fuze for use in underwater explosive devices having a fuze body engageable in the explosive device and having an axial bore therethrough, the combination of a cylindrical casing attached to one end of said fuze body, a spring compressor element having a tube slideable in said bore and a sleeve fixed to the end of said tube within said cylindrical casing, said sleeve having a plurality of apertures in the wall thereof spaced circum-

ferentially and axially of said sleeve from each other, wedges on the end of said sleeve opposite said tube projecting radially into said sleeve, a fluted tube attached within the end of said cylindrical casing opposite said fuze body and extending within the end of said sleeve, said fluted tube having a groove around the outside of the end thereof within said sleeve into which said wedges project, each of the flutings being vertically aligned with one of said apertures in said sleeve, a detent locking ball in the end of the wall of said fluted tube within said sleeve, a primer piston slideable within said fluted tube having a groove therein in which said locking detent ball is engaged, and a spring between said primer piston and said sleeve normally in the unstressed condition.
